UNITED STATES PATENT OFFICE

GEORGE H. FORSYTH, OF CHICAGO, ILLINOIS.

WINDOW CONSTRUCTION.

1,086,320.

Specification of Letters Patent.

Patented Feb. 3, 1914.

Application filed February 6, 1909. Serial No. 476,470.

To all whom it may concern:

Be it known that I, GEORGE H. FORSYTH, a citizen of the United States, residing at Chicago, in the county of Cook and State of Illinois, have invented certain new and useful Improvements in Window Constructions, of which the following is a specification.

This invention relates to window constructions, and more especially windows of that type wherein the sash frames are made of hollow bent or folded sheet metal, such as are coming into use in connection with railway cars and other situations where a light, strong and fireproof construction is desired.

The general object of the invention is to provide a simple, easily operated and snug-fitting window; and the constructional features of the invention will be readily understood when considered in connection with the accompanying drawing, in which,—

Figure 1 is a vertical transverse section through the upper portion of the window, showing the two glazed sash. Fig. 2 is a similar section through the lower portion of the window and sill. Fig. 3 is a side elevation, broken out, of one side of one sash member and its shoe. Fig. 4 is a horizontal section, enlarged, through one side of the window, showing twin sash members, and their manner and means of engagement with the guide of the frame.

Referring to the drawing, 1 (Fig. 4) designates an upright post of substantially I-beam formation, and 2 a covering or finishing strip applied to the side thereof which is adjacent to the window opening. 3 designates a portion of an interior finishing strip that covers the post 1 between adjacent window openings. Applied to the strips 2 and 3 is a corrugated sheet metal strip designated as an entirety by 4, which is suitably grooved longitudinally to form grooves or channels 5, 6 and 7, for a pair of outer and inner sash members 8 and 9, respectively, and a curtain fixture indicated at 10. It will be observed by reference to the enlarged view, Fig. 4, that the guide-grooves 5 and 6 have straight and oblique guide walls 5^a and 5^b and 6^a and 6^b, the purpose of the oblique walls being to automatically force the opposite sides of the sash members into snug engagement with the straight walls to secure a tight fit.

55 The stiles and lower transverse bar of each sash frame are formed of sheet metal

suitably bent to present a hollow structure, and are provided with protuberant ribs on their inner edges designed to form an attachment or anchorage for elastic metal glazing strips or clamps, this latter forming one of the features of the invention. Referring to the lower transverse bar of the sash 8, as shown in Fig. 2, it will be seen that this comprises a hollow sheet metal member 11, the two margins of which are bent inwardly on the inner edge of the bar, as shown at 11^a and are then flared outwardly, as shown at 11^b, producing a dovetail formation, said outwardly flared edges being secured together by a correspondingly bent cap 12, forming a protuberant rib. Embracing this latter is a hollow metal clamp 13, open on its inner edge to receive the lower margin of the glass under spring tension. At intervals spring tongues 13^a are punched or struck up out of the top wall of the clamp 13 to form a spring cushion for the edge of the glass. The lower bar 14 of the sash member 9 illustrates a slightly modified formation, wherein the inner wall of the bar is continuous, being formed with the protuberant rib 14^a, and the margins of the metal being overlapped in the bottom wall of the member, as shown at 14^b. To 85 the protuberant rib 14^a is applied the same elastic metal clamp 13 for holding the lower edge of the glazing.

The upper transverse bar is so formed as to itself constitute an elastic glass-holding means. The bar of the sash 8 has a pair of sheet metal sides 15 swung inwardly at their inner margins, as shown at 15^a, to form an inner clamp for the glass, their outer edges being provided with reentrant channels 16 that are engaged by inwardly extending ribs 17 of an outer marginal cover or cap 18, said cap being bent back upon itself along its outer margins at 18^a and having inwardly extending elastic margins 19 which grip and clamp the upper marginal portion of the glass. In the form of the upper bar shown at the right in Fig. 1 in connection with the sash 9, the reentrant channels 20 and spring margins 21 are made integral with the side walls 22 of the sash bar, and the cap 23 has its margins bent back upon themselves at 23^a and a marginal flange 24 snugly fitting the channel 20. The purpose of the caps 18 and 20 is to provide 110 a removable closure for the upper end of the sash frame, whereby the glazing may

be dropped into place, and the upper edge of the sash bar subsequently covered.

Referring now to the means for guiding the vertical bars or stiles of the sash frames 5 in the guide-channels of the casing, Fig. 4 shows a bar of slightly different construction. In both cases, the stile proper consists of a hollow sheet metal member so formed as to present a vertical channel in its outer 10 edge. The stile 25, shown in connection with the sash 8, is formed substantially as the lower bar 11, except for the presence of a deep marginal channel 26 formed by folding the metal inwardly, thus producing a 15 pair of opposed hollow side walls 27 and 28 into which is fitted, at the corners of the sash frame, L-shaped connectors 29 of channel form in cross-section. The stile 30, shown in connection with the sash 9, is formed substantially 20 like the stile 25. Between the stile 25 and its guide-groove 5 is located a sheet metal shoe, which is so bent as to provide parallel marginal portions 33 and 34 which engage the side walls of the channel 25 25 of the stile, a straight transverse wall 35 bent back upon itself along its margin 35^a, an oblique wall 36, and an outer side wall 37 of double thickness, integral with which latter are formed inwardly extending finger 30 hooks 38 for use in withdrawing the sash and shoe from the frame when desired. Between the transverse wall 35 of the shoe and the bottom transverse wall of the channel 26 is interposed a bow-spring 39, normally 35 tending to force said members apart and produce a snug fit of the shoe in the guide. The shoe shown in connection with the stile 30 is constructed on the same principle, although slightly differently formed, having 40 parallel walls 40 and 41 engaging the side walls of the channel 31, an oblique wall 42 engaging the oblique wall 6^b of the channel, and an outer side wall 43 of double thickness, one margin of the shoe being bent 45 transversely to form an abutment 44 for the leaf spring 45 whereby the shoe is forced into engagement with the guide. It will be noticed that the engagement of the oblique walls of the shoes with the oblique walls of 50 their respective guides produces a wedging action tending to crowd the outer sides of the stiles into engagement with the vertical walls of their respective guides.

The stile members are formed with protuberant ribs on their inner edges for the attachment of the glass-holding strips or clamps 46 and 47 which are similar in function to the clamps 13. In connection with the sash 8 I have shown the same formation 55 as in connection with the lower bar (Fig. 2). In connection with the sash 9, I have shown a slightly modified holding means, the connecting strip 48 having integral inwardly turned folds 49 embracing the outer 60 wardly bent margins of the stile and being

further provided with downwardly and outwardly bent margins 50 beneath which hook the lower inwardly turned margins 51 of the clamp 47. Spring glass cushioning tongues 48^a are struck up from the strip 48, 70 similar in function to the tongues 13^a.

The inner side of the window casing is provided with a readily detachable finishing board or strip 52 (Fig. 1) to which is secured the housing 53 of the curtain fixture 75 roller 54, said finishing strip 52 lying opposite the upper ends of the sash members 8 and 9. By removing this strip, and compressing the shoes inwardly toward the stiles by means of the finger hooks 38 or otherwise, the sash members can readily be removed from their guides, which operation is an advantageous one where the car is to be converted from winter to summer service.

It will be noticed that the glass is secured wholly by elastic clamps which, in the case of the upper cross-bars, are integral with the latter and, in the case of the stiles and lower bars, are so formed as to be capable of being readily mounted in place on 80 the marginal ribs. This affords an exceedingly simple and easy manner and means of securing the glass without necessity of screws or other fastening devices; while the glass, being held on all sides under spring tension, is proof against rattling. The provision of shoes between the sash stiles and their guides which engage said stiles both on the inner and outer sides of their side walls, is also of advantage in holding the 85 sash members securely against lateral yield relative to their guides, and in making an extra tight sash. The ends of the shoes are bent transversely to overlap the ends of the sash at the corners of the latter, as shown at 90 37^a, which both causes the shoes to move with the sash and holds the cap members in place.

I claim:

1. The combination with a sash frame 110 member having a protuberant rib on its inner margin, of a glass-holding strip mounted upon and embracing the rib and having tongues outstanding in the plane of the rib to support the edge of the glass, said strip 115 elastically engaging the glass on both sides of the same, substantially as described.

2. The combination with a sash frame member having an integral protuberant rib of dovetail form in cross-section on its inner margin, of a glass-holding strip having a base adapted to snugly fit over said rib, and elastic inwardly bent margins adapted to clamp the glass.

3. The combination of a sash frame 125 member, and a glass holding strip having elastic inwardly bent portions adapted to grip the glass on both sides thereof, one of said elements having a protuberant rib and the other having a groove coöperating with 130

said rib whereby to effect a connection between said elements, substantially as described.

4. The combination of a sash frame member, and a glass holding strip having elastic inwardly bent marginal portions adapted to grip the glass on both sides thereof, the sash frame member and the glass holding strip having a dove-tail connection one with the other, substantially as described.

5. The combination of a sash frame member, and a glass holding strip mounted there-

on and having elastic inwardly bent portions adapted to grip the glass on both sides thereof, the sash member and the glass holding strip having coacting wedge surfaces tending when assembled to draw the elements into a snug engagement, substantially as described. 15
